UNITED STATES PATENT OFFICE.

OLIVER W. BALDWIN, OF GARY, INDIANA.

DESIGN FOR A COMBINATION SALT AND PEPPER SHAKER.

Application filed February 9, 1927. Serial No. 20,656. Term of patent 7 years.

To all whom it may concern:

Be it known that I, OLIVER W. BALDWIN, a citizen of the United States, residing at Gary, in the county of Lake and State of Indiana, have invented a new, original, and ornamental Design for Combination Salt and Pepper Shaker, of which the following is a specification, reference being had to the accompanying drawing, forming part thereof.

I claim:

The ornamental design for a combination salt and pepper shaker, as shown.

OLIVER W. BALDWIN.
